(No Model.)

E. BLACKMAN.

WICK RAISER FOR CENTRAL DRAFT LAMPS.

No. 461,101.

Patented Oct. 13, 1891.

HIS ATTORNEY

UNITED STATES PATENT OFFICE.

EBENEZER BLACKMAN, OF BROOKLYN, NEW YORK, ASSIGNOR OF ONE-HALF
TO EDWIN H. BROWN, OF SAME PLACE.

WICK-RAISER FOR CENTRAL-DRAFT LAMPS.

SPECIFICATION forming part of Letters Patent No. 461,101, dated October 18, 1891.

Application filed August 26, 1890. Serial No. 363,104. (No model.)

To all whom it may concern:

Be it known that I, EBENEZER BLACKMAN, of Brooklyn, county of Kings, and State of New York, have invented a certain new and 5 useful Improvement in Wick - Raisers, of which the following is a specification.

This invention relates to wick-raisers for central-draftlamps; and it consists of a slotted central draft-tube, a wick-carrier comprising 10 divergent resilient arms constructed to engage a wick, upwardly-extending portions on the arms for disengaging the arms from the wick, and means for moving the carrier vertically.

15 I will describe a wick-raiser embodying my improvement, and then point out the novel features in the claims.

In the accompanying drawings, Figure 1 is 20 a vertical section of a lamp embodying my invention. Fig. 2 is an enlarged vertical section of a wick-tube embodying my invention. Fig. 3 is a vertical section showing a modified construction. Fig. 4 is a transverse section on the line $\alpha\alpha$ of Fig. 2, and Fig. 5 is a trans- 25 verse section on the line $\gamma\gamma$ of Fig. 3.

Referring by letter to the drawings, A designates a lamp-fount having a base A', provided with openings for the admission of air.

B B' designate the outer and inner shells of 30 a wick-tube, and B² shows the wick therein. The inner shell B' constitutes a central draft-tube. As shown in Fig. 1, it extends upward from the bottom of the fount and communicates and receives air from the base of the 35 lamp. A perforated thimble A² extends into the upper portion of the inner draft-tube B' and rests upon an annular bead or stop a.

C designates a wick-raiser comprising an arm or arms c movable vertically within the 40 draft-tube B'. The arms c are preferably of resilient metal divergent from an operating rod or bar c' and provided at the outer side of the free ends with points or pins c², which pass through vertical slots c³ in the tube B' to engage with the wick. It is obvious that when the arms c are moved up and down the wick will be correspondingly moved. In the drawings I have shown some of the means by which the arms c may be operated. For instance, in 45 Fig. 1 I have shown the rod c' as having a rotary connection with the arms c and having a

threaded portion engaging in an interiorally-threaded boss d on a bar d', extending across and secured to the bottom of the tube B'. In this example the wick-carrier may be operated by rotating the rod c'. In Fig. 3 the rod c' is not threaded, but passes through a guide in the bar d'. In this example it is obvious that by simply pushing upward or pulling downward the rod c' the carrier will be similarly moved. In Fig. 2 the rod c' is shown in the form of a rack-bar, the teeth of which engage with a pinion e on a shaft e', journaled through the wick-tube and provided at its outer end with a finger-piece e², by means of 60 which the shaft and pinion may be rotated to move the wick-carrier up or down.

In Figs. 1 and 3 a cylindric wick may be used; but in Fig. 2 I prefer to use two wicks, which, when placed in position, form in effect 70 a single cylindric wick, and by employing the two wicks the shaft e' may extend between the adjacent edges and not interfere with the movement of the wick. The draft-tube B', as shown in Fig. 2, is not intended to extend 75 through the fount, but is closed at its lower end, excepting a guide-opening for the bar c', and terminates approximately on a level with the collar of the fount, into which the burner is fitted. Air is admitted to the lower por- 80 tion of the tube B', in this example, through a lateral opening or openings f, the walls f' of which extend across the space between the shells B B'.

In some of the examples of my improvement 85 I find it desirable to employ an annular stay D. This stay D surrounds a portion of the wick and is adapted to move with it inside of the shell B. It is provided at its upper edge with inwardly-projecting prongs f², which engage with the wick. This stay serves to hold the wick closely against the pin c², and it may be perforated for the passage of oil when it extends into the fount, as in Fig. 1.

In Fig. 3 I have not shown the annular stay; 95 but in lieu thereof I employ segmental plates g, attached to the arms c and provided with a series of pins c².

It is sometimes desirable to move the wick-carrier without imparting motion to the wick— 100 for instance, to change the position of engagement with the wick. For this purpose it is

necessary to move the pins c^2 from the wick, and as a means thereof I provide each of the resilient arms c with an upwardly-extending portion or rod E , having locking device, (here 5 shown in the form of a ball g' at the top.) By forcing the upper ends of the rods E toward each other the ends of the arms c will be caused to approach and draw the pins c^2 out of the wick. The rods E may be held in this position 10 by hand and the carrier moved, as desired, or the rods may be crossed, as shown in dotted lines, Figs. 1 and 2, so that the balls g' pass and interlock or engage with each other.

Having described my invention, what I desire to secure by Letters Patent is—

1. In a lamp, the combination, with a wick-tube having a slotted inner shell forming a central draft-tube, of a wick-carrier comprising divergent resilient arms constructed to 20 engage a wick, means for moving the carrier vertically, and upwardly-extending portions on said arms for disengaging the arms from the wick, substantially as specified.

2. In a lamp, the combination, with a wick-tube having a slotted inner shell forming a central draft-tube, of a wick-carrier comprising divergent resilient arms constructed to engage with a wick, means, substantially such as described, for moving the carrier vertically within the draft-tube, rods extending upward 30 from said arms, and locking devices on the rods, substantially as specified.

3. In a lamp, the combination, with a wick-tube having a slotted inner shell forming a central draft-tube, of a wick-carrier engaging 35 a wick and movable vertically within the draft-tube, and an annular stay surrounding and movable with the wick, substantially as specified.

In testimony whereof I have signed my 40 name to this specification in the presence of two subscribing witnesses.

EBENEZER BLACKMAN.
